FABRIC TAKE-UP DEVICE FOR FLAT KNITTING MACHINES

James L. Getaz, Maryville, Tenn., assignor to Interwoven Stock'ng Company, New Brunswick, N. J., a corporation of New Jersey

Application January 28, 1937, Serial No. 122,872

5 Claims. (Cl. 66—149)

This invention relates to fabric take-up devices for use with flat knitting machines and more particularly with machines for knitting full fashioned hosiery and it is an object of this invention to provide an improved fabric take-up device for machines for knitting full fashioned hosiery, the device being of such construction that injury to the fabric by the welt hook bar is prevented. It is also an object of this invention

10 to provide a fabric take-up device having a drum upon which the fabric is wound and in which the welt hook bar is received whereby injury to the fabric is prevented.

Figure 1 is a vertical longitudinal sectional view 15 of a fabric take-up mechanism in accordance with this invention; and

Figures 2 and 3 are vertical transverse sectional views of the take-up mechanism shown in Figure 1, taken as on lines 2—2 and 3—3, respectively of Figure 1.

In the drawing there is shown a fabric take-up device in accordance with this invention for holding knitted fabric continuously under tension as the fabric leaves the needle bars of the knitting machine. The take-up device shown comprises a drum 18 journaled on a shaft 11 rotatably mounted in bearings 12 attached to the machine frame or other suitable support. Fixed on the shaft 11 at the ends of the drum 18 are pulleys 13 having attached thereto, in position to be wound thereon, bands or strips 16 of webbing which are also connected to a welt hook bar 42 of usual construction. Also fixed on the shaft 11 is a pulley 44 to which is attached a band or strip (not shown) which is wrapped about the pulley 44 one or more times and connected to a weight (not shown) in such manner that the weight serves to rotate the pulley 44, shaft 11 and pulleys 13. The drum 18 is grooved longitudinally at 18' to receive the welt hook bar 42. To hold the drum in position to receive the welt hook bar in the groove the drum is provided with spaced abutments 18a forming a groove 18b to be engaged by a latch 45 pivotally mounted on a bracket 46 fixed on a bearing 12. The latch 45 is provided with an arm 45' which projects into the path of the welt hook bar 42

so that as the welt hook bar is drawn into the groove 18' in the drum 18 the welt hook bar operates the latch 45 to release the drum 18 so the drum is free to be rotated by the welt hook bar to wind the fabric thereon. Should the drum 18 be rotated more than a single revolution the welt hook bar 42 maintains the latch disengaged as the abutments 18a pass the latch 45. 5

What is claimed is—

1. In a knitting machine, a rotatable drum, a 10 welt hook bar and means operating said bar to rotate said drum to wind fabric thereon.

2. In a knitting machine, a rotatable drum, latch means preventing rotation of said drum, a welt hook bar and means operating said bar 15 to release said latch and rotate said drum to wind fabric thereon.

3. In a knitting machine, a drum rotatable for winding fabric thereon, said drum being grooved to receive a welt hook bar, latch means for holding said drum stationary, a welt hook bar, means 20 for operating said welt hook bar to draw fabric to the drum and means for operating said latch by said welt hook bar to permit rotation of said drum by said bar operating means. 25

4. In a knitting machine, a drum rotatable for winding fabric thereon, said drum being grooved to receive a welt hook bar, latch means for holding said drum stationary, a welt hook bar, and 30 operating means for engaging said bar in said groove and operating said latch to release said drum, said bar operating means causing said bar to rotate said drum.

5. In a knitting machine, a welt hook bar, a drum rotatable for winding fabric thereon, said 35 drum being slotted to receive the welt hook bar with the hooks of said bar drawn within said drum, latch means for holding said drum stationary in position to receive the welt hook bar in the slot and means for operating said welt hook bar to draw fabric to said drum, said operating means being arranged to draw said welt hook bar into said slot and cause said welt hook bar to operate said latch means to release said drum for rotation and rotate said drum for winding 40 fabric thereon. 45

JAMES L. GETAZ.
